UNITED STATES PATENT OFFICE.

ERIC MONTAGUE SMITH, OF EASTCOTE, ENGLAND.

ROTARY SHEARING AND OTHER HAND-OPERATED TOOL.

Application filed June 13, 1924. Serial No. 719,751.

To all whom it may concern:

Be it known that I, ERIC MONTAGUE SMITH, a subject of the King of Great Britain, residing at Sigers, Eastcote, in the county of Middlesex, England, have invented certain new and useful Improvements in or Relating to Rotary Shearing and other Hand-Operated Tools, of which the following is a specification.

10 This invention relates to hand-operated rotary shearing tools having either or both of the rotary cutters peripherally milled or dentated and the invention has reference more particularly to new or improved arrangements for actuating, or applying the driving force to, such tools.

According to the present invention, instead of employing the usual pawl and ratchet wheel as the driving means, I apply 20 the driving force direct to the milled or dentated periphery of one or both of the rotary cutters by means of a member or members adapted for direct engagement therewith. Such drive is positive in action 25 and has the advantage (inter alia) over the usual arrangement of enabling the operator to make very short strokes with the driving lever or handle where such is desirable or necessary for example when 30 operating the tool in a limited space such as a corner or in an angle where any great angular movement of the driving lever would be difficult or impossible.

Furthermore the use of this invention 35 considerably cheapens the cost of manufacture of such shearing tools, since the additional pawl and ratchet wheel on one or each of the cutters are dispensed with.

The present invention will be more 40 clearly understood by reference to the accompanying drawings wherein:

Fig. 1 is a front view in elevation and

Fig. 2 is a side view in elevation of a hand-operated rotary shearing tool having 45 one driven and one free running cutter.

In these drawings:

A and B designate two peripherally milled or dentated rotary cutters mounted in the usual manner in the frame C of a 50 rotary shearing tool. A pair of links or cheeks D are rotatively mounted on the spindle A¹ of the cutter A, and between these cheeks D towards the other end thereof is pivoted a driving element E secured to 55 the operating lever or handle F. This driving element E may terminate at its

lower end in a sharp nose or tooth E¹ (as shown) or the said member E may be serrated or milled over the whole or a part of the under surface thereof so as to engage 60 simultaneously a plurality of the dentations on the driven cutter A. A stop or abutment G is provided on one of the cheeks D to limit the backward movement of the driving element E upon the rearward or idle stroke 65 of the handle F, so as to prevent engagement of said driving element E with the cutter A during such rearward stroke.

The periphery of the driven cutter or of both said cutters may be of any usual or 70 suitable configuration in section, e. g. perfectly flat or V-shaped, the engaging part of the driving element E being formed to correspond.

The driving means according to this 75 invention may obviously be applied to both of the rotary cutters in a portable shearing tool having two operating handles.

What I claim is:

1. A shearing tool comprising a frame, a 80 plurality of rotary cutters mounted therein with their cutting edges in operative relation with respect to one another, one of said cutters having its periphery dentated, and a pivoted operating lever carried by the 85 frame and adapted to engage the dentations of the cutter whereby to drive the same.

2. A hand operated rotary shearing tool comprising a peripherally milled or dentated driven cutter, a freely running rotary 90 cutter co-acting therewith, a driving element adapted for direct engagement with the periphery of said driven cutter upon the driving stroke and means, movable about the axis of the driven cutter, to support 95 said driving element.

3. A hand operated rotary shearing tool according to claim 2 having the driving element pivotally mounted with respect to its supporting frame so as to be capable of 100 movement towards and away from the periphery of the driven cutter upon the driving and the return stroke respectively of the operating handle.

4. A shearing tool comprising a frame, 105 a freely rotatable cutter mounted therein, a driven cutter rotatably mounted in operative relation with respect to the first mentioned cutter, and provided with indentations on its periphery, a pivoted operating 110 lever mounted in operative relation with respect to the driven cutter, and a tooth

carried by the lever and adapted to engage the dentation of the cutter when the lever is moved on its pivot, whereby to drive the cutter.

5. A shearing tool comprising a frame, a freely rotatable cutter mounted therein, a driven cutter mounted in operative relation with respect to the first mentioned cutter and having a dentated periphery, links

10 mounted on either side of the driven cutter

for pivotal movement about the axis thereof, an operating lever pivotally carried by the links in operative relation with respect to the dentated periphery of the cutter, a tooth carried by the lever and adapted to engage the dentations of the cutter when the lever is operated, and a lug carried by one of the links to limit the pivotal movement of the lever.

ERIC MONTAGUE SMITH.
